UNITED STATES PATENT OFFICE.

FRANCIS J. DOYLE, OF CHICAGO, ILLINOIS.

LOCOMOTIVE.

1,080,103.

Specification of Letters Patent.

Patented Dec. 2, 1913.

Application filed February 21, 1910. Serial No. 545,236.

To all whom it may concern:

Be it known that I, FRANCIS J. DOYLE, a citizen of the United States, residing in the city of Chicago, county of Cook, and State 5 of Illinois, have invented certain new and useful Improvements in Locomotives, of which the following is a specification:

This invention relates to improvements in locomotives and has among its salient objects to provide a construction in which a maximum of heating efficiency is obtained from the fuel, and in which smoke, cinders, soot, etc., are substantially eliminated; to provide a construction in which the fuel body is distilled, as contradistinguished from a direct burning, and in which the gases of distillation are ignited by the initial flame from the fuel body; to provide a construction in which the fire chamber is provided with a single dependent bridge wall, which divides the fire chamber into two zones, and also holds the gases of distillation in one of said zones until they are heated to a relatively high temperature; to 15 provide a construction in which any pronounced induced draft through the fire chamber is substantially eliminated, and in which the outlet area of the fire tubes is restricted and varied at the will of the engineer; to provide an improved mechanism for accomplishing the last named object; to provide means for forcing regulated quantities of air into the fire zones, both above and below the grate level; to provide a construction which effectively utilizes a major portion of the heat units generated in raising the temperature of the water in the boiler, instead of permitting a large portion 20 of said heat units to pass out through the stack and thereby wasted; to provide a construction which is particularly adapted for use with standard types of locomotives and without necessitating any substantial reconstruction of the latter; and in general to 25 provide an improved construction of the character referred to.

The invention consists in the matters hereinafter described, and more particularly pointed out in the appended claim.

50 In the drawings—Figure 1 is a fragmentary view, partly in side elevation and partly in vertical section, of a locomotive equipped with my invention; Fig. 2 is a vertical sectional view of the rear end of the locomotive and showing more particularly the construction of the fire box; Fig. 3 is a

transverse horizontal sectional view taken centrally through Fig. 2; Figs. 4 and 5 are views similar to Figs. 2 and 3 respectively, but showing a slightly modified construction; Fig. 6 is an enlarged transverse vertical sectional view of the mechanism for restricting the outlets of the fire tubes; Fig. 7 is a fragmentary sectional view, taken substantially at right angles to Fig. 6 and through the central portion of the latter.

In the present invention, the fuel is distilled instead of being burned directly, and the gases of distillation ignited and mixed with the proper amount of air to effectively oxidize the gases. Accordingly, a relatively deep fuel body should be maintained within the fire chamber, and the air should be forced in at a nominal pressure, as contradistinguished from strong blasts. The gases of distillation are held within the fire zones until heated to such temperature as to obviate smoke and soot, and are further retarded until substantially oxidized. The major portion of the heat units generated 70 are effectively utilized in raising the temperature of the water in the boiler, and the distilled gases are prevented from passing out through the stack until the heat units generated have been so utilized.

Referring to the drawings, 1 designates as a whole the boiler shell of the locomotive, 2 the front end, 3 the cab, 4 the main fire chamber, 5 the stack, 6 the main driving cylinders, 7 the steam fountain in the cab, 80 8 the fire tubes, 9 the ash pit, 10 the steam pipe, 11 the grate, 12 the exhaust steam nozzle, 13 the running board, and 14 the rear tube sheet.

As an important feature of the present invention, within the main fire chamber is formed a dependent wall member 15, which extends entirely across the fire chamber near the front end of the latter, and terminates some distance above the grate level. This 95 wall or partition 15 divides the main fire chamber into two zones, designated 16 and 17 respectively. In practice, a relatively deep fuel body is maintained on the grate, and the gases of distillation as they rise 100 from the fuel pass upwardly into the chamber 17, which may be called the magazine, and thence, after being very highly heated are compelled to pass down over or through the fuel body into the front chamber 16, 110 which may be termed the combustion chamber, and are there substantially oxidized.

As shown in Figs. 2 and 3, the wall or partition member 15 is formed of fire brick, which are supported between horizontally extending water tubes 18, which communicate at either end with the side water legs 19 of the main boiler.

In order to prevent any pronounced induced draft through the fire chamber, the exhaust nozzle 12 is provided with an extension 20, which projects into the lower end of the stack 5. Preferably a conical screen 21 incloses the extension 20, as shown more clearly in Fig. 1.

The manner of restricting the flue outlet area of the tubes may be described as follows: To the front tube sheet 22 is secured a cylindrical hood 23 of slightly less diameter than the boiler shell, open at its forward end and provided with an inturned flange 24. Within this hood is fixedly mounted a front plate member 25, provided with a plurality of restricted apertures 26 which register with the corresponding ends of the fire tubes 8. With the stationary plate 25 operates a movable plate 27, provided with a plurality of similar apertures 29. This movable plate is pivotally connected at its axis to the stationary plate, as shown at 30, and is also provided at its periphery with a plurality of short segmental slots 31, adapted to receive studs 32, carried by the stationary plate. The upper ends of the plates are apertured to receive the steam pipe 10, the outer plate being provided with a sufficiently large aperture to permit of limited rotary movement thereof. The arrangement is such that when the plates are in normal position, the apertures thereof register with each other, but when the movable plate is rotated the apertures of the stationary plate may be closed or partially closed, to the extent desired.

Describing now the mechanism for rotating the movable plate, upon the upper side 45 of the boiler shell is rigidly fixed a pair of brackets, 33, 34, to which is connected a hollow tubular standard 35, within which is mounted a rock shaft 36. The lower end of this rock shaft is connected to a bell crank 50 lever 37, which actuates a connecting rod 38, the inner end of which is secured as shown at 39 to the movable plate. To the upper end of the rock shaft 36 is connected a shifting lever 40, which extends through 55 the hollow handrail 41 into the cab, in order that it may be accessible to the engineer. It will be noted that the connection 39 of the rod 38 is eccentric to the axis of the movable

plate, and accordingly the actuation of the rod will rotate the movable plate.

In order to supply a sufficient quantity of air to the fire, upon the running board of the engine is mounted a steam actuated pump 42, which is connected by a steam pipe 43 to the fountain 7. Within the upper end of the cab is mounted an air fan 44, which is driven by means of suitable belts 45 and 46 by the engine 42. The mountings of these belts are of ordinary construction and need not be described in detail. To the fan 44 is connected a main air pipe 47, which leads to the air nozzles 48 and 49, delivering to the fire above and below the grate respectively. Similarly, a branch pipe 48' leads to the lower end of the combustion chamber 16. The supply of air to the fire may, of course, be controlled by regulating the fan 44 and engine 42.

In Figs. 4 and 5 I have shown a slightly modified construction of the wall or partition within the fire chamber. In this instance the wall 15' takes the form of a water leg, which extends transversely of the fire box, in the manner heretofore described, and communicates at its sides and upper end with the boiler space. This construction not only adds an increased heating surface, but also prevents the partition from being destroyed by heating.

The operation of the invention is apparent from the description and need not be described in detail.

The invention is not limited to the details of construction shown, except as set forth in the appended claim.

I claim as my invention:

In a locomotive, the combination with a fire chamber, a grate at the lower end of said chamber and a closed ash pit below said grate, flues extending from the front end of said fire chamber, a wall depending from the roof of said fire chamber and terminating within a short distance of the grate and disposed in front of but spaced only a short distance from the inlet ends of said flues, adjustable means for restricting the outlets of said flues, means for positively forcing air into said closed ash pit and into said fire chamber and into the restricted throat between said depending wall and grate.

FRANCIS J. DOYLE.
